WRITING INSTRUMENT

Donald W. Doman, Janesville, Wis., assignor to The Parker Pen Company, Janesville, Wis., a corporation of Wisconsin

Filed May 13, 1960, Ser. No. 60,574

Term of patent 14 years

(Cl. D74—17)

Fig. 1 is a side elevational view of a writing instrument embodying my new design;

Fig. 2 is a front elevational view thereof;

Fig. 3 is a side elevational view thereof, showing the side opposite to that of Figure 1;

Fig. 4 is a rear elevational view thereof; and

Fig. 5 is a top plan view of the writing instrument as seen in Fig. 2.

The essential features of the design reside in the portions shown in solid lines on the drawing.

I claim:

The ornamental design for a writing instrument, as shown and described.
